(57) **CLAIM**

The ornamental design for a “blending jar,” as shown and described.

DESCRIPTION

FIG. 1 is a top perspective view of a blending jar according to the present invention;

FIG. 2 is an elevated top perspective view thereof;

FIG. 3 is a bottom perspective view thereof;

FIG. 4 is a front view thereof;

FIG. 5 is a rear view thereof;

FIG. 6 is a right side view thereof;

FIG. 7 is a left side view thereof;

FIG. 8 is a top view thereof;

FIG. 9 is a bottom view thereof; and,

FIG. 10 is a sectional side view, taken along the line 10-10 of FIG. 9, thereof.

The broken lines shown in the drawings are for illustrative purposes only and form no part of the claimed design.
